Lighting, April 1957, page 33, upper righthand corner, item No. 5, lantern.

Lighting, October 1957, page 40, upper righthand corner, revolving light.

Fig. 1 is a perspective view of a combined lamp and rotary beacon showing my new design, with two of the window panes fragmentarily shown to better illustrate the interior portions thereof.

Fig. 2 is a perspective view from a different position from that of Fig. 1 with the door open, and

Fig. 3 is a reduced sectional view taken substantially along the line 3—3 of Fig. 2.

The sides of the combined lamp and rotary beacon not shown, are substantially the same in appearance as the sides shown.

The dominant features of my design reside in the portions shown in full lines.
